UNITED STATES PATENT OFFICE.

NELSON G. GOREAU, OF NEW ORLEANS, LOUISIANA.

WATER-HEATER.

1,026,030.

Specification of Letters Patent.

Patented May 14, 1912.

Application filed June 8, 1909. Serial No. 500,824.

To all whom it may concern:

Be it known that I, NELSON G. GOREAU, a citizen of the United States, residing at New Orleans, in the parish of Orleans and State of Louisiana, have invented a certain new and useful Improvement in Water-Heaters, of which the following is a specification.

My invention relates to water heaters of the class generally known as instantaneous water heaters.

The object of the invention is to provide a new and efficient heating coil.

The foregoing and other advantages of the invention are hereafter fully explained in connection with a detailed description of the drawing which is a vertical section in diagrammatic form of an exemplifying apparatus embodying the invention.

Reference character 1 designates a casing in which the heating coil 2 is mounted. The coil consists of an upper flat spiral 3, the center portion of which is continued to form a downwardly flaring conical spiral 4. The pipe constituting the coil is flattened and the longer axis arranged vertically as shown, so that the coils of the pipe may be arranged close together and so that a very large portion of the pipe surface is directly exposed to the heat from the burners. The coil may be arranged in many different ways. By flattening the tube composing the coil and arranging the turns of the coil so that a space is left between the turn, a very large surface of the coil is exposed to the heat from the burners. These coils become quickly coated with soot or carbon which readily absorbs the heat and communicates it to the coil. My heating coil consisting of a flattened tube, the convolutions of which are spaced apart in the manner shown or any reasonable variation thereof is an exceedingly efficient heating element.

Water enters the coil at 5 and passes out at 6. The end 6 of the coil communicates through a valve 7 with the motor cylinder 8 through inlet port 9. The cylinder also has an outlet port 10 which is connected to the service pipe through which water is led to different faucets to be supplied. The outlet port 10 may, if desired, be somewhat restricted by means of a flange 11 cast in the cylinder. Within the cylinder is piston 12, connected to valve stem 13. The piston is provided with a port or by-pass 14 in which valve 15 is seated in such a way that

a certain amount of water is allowed to pass through the port without raising the piston. The valve 15 is urged to its seat by a spring 16. The stem of valve 15 is threaded and a nut 15^a on the stem serves to adjust the tension of the spring. The upper end of the valve stem 13 above the piston carries a thermostat 17, consisting of a series of dished brass disks 18 arranged in pairs, each pair being encircled by a steel ring 19. The several pairs of disks are secured together as shown and any convenient number of pairs may be used to give the desired expansion. In the upper end of the cylinder is a screw 20 provided with a lock nut, serving as an adjustable stop to limit the movement of the thermostat.

The apparatus so far described operates as follows: When any service valve is opened water is drawn through the coil and as soon as it passes in any considerable quantity through inlet port 9 into the cylinder the piston 12 is raised until the upper end of the thermostat engages the adjustable stop. The spring controlling the by-pass valve 15 is made of sufficient strength to cause the water to raise the piston before the valve is opened. The valve having reached its limit of travel the fluid pressure raises the by-pass valve 15 and water flows through the piston and discharge port 10 to the service pipe. The upward movement of the piston lights the main burners under the coil as will be hereafter described and the water is rapidly heated. As the heated water passes around the thermostat its dished brass plates expand and being retained by the steel rings 19 this expansion results in a separation of the center points of the plates, that is an elongation of the thermostat. This elongation of the thermostat is proportional to the heat of the water and as the upper end of the thermostat is in engagement with stop 20 the valve stem 13 is moved downward as the water heats and is permitted to move upward as the water cools so that an automatic regulation of the temperature of the water is effected. When the service valve is closed water ceases to flow through the motor cylinder. A small amount of water may still pass through the by-pass valve which does not seat fully and the piston 12 therefore descends under influence of gravity and a spring which will be later described. This movement of the piston shuts off the main

gas burners and heating of the water is discontinued.

Below the motor is the gas valve 30 which has two ports: 31 the main port, and 32 the pilot port. Gas enters at 33. Port 31 is closed by the main gas valve 34. A spring 35 compressed between the valve and the valve casing tends to close the valve and to lower the valve stem 13 on which the valve 10 is mounted. The lower end 36 of valve stem 13 serves as a valve for the pilot port 32. This valve 36 is arranged so that it does not fully close. Gas passes from port 31 to a header 37 with which the main burners 38 15 are connected and from port 32 past a regulating valve 39 through pipe 40 to the pilot burner 41.

The pilot burner is continually lighted and may be regulated by valve 39 so that 20 the flame is very small, requiring a minimum quantity of gas. When valve stem 13 is raised by the motor piston the main valve 34 is raised and gas is admitted to the main burners 38. The pilot burner takes its gas 25 from the same source as the main burners and when the pressure in the supply pipe 33 is reduced by opening the main valve the pilot light would frequently be extinguished because of the reduction of pressure in the supply pipe and because of the 30 rush of air and gas from the main burners

and this is especially liable to occur when the pilot light is very small. This occurrence is prevented in my invention by the arrangement of the pilot valve 36 which 35 opens concurrently with the main valve. Therefore whenever the main valve is opened the pilot light receives an additional quantity of gas which prevents it from being extinguished. 40

The motor cylinder may be conveniently supported by a bracket 50 secured to the valve casing 30.

Other advantages of the structure will be apparent to persons versed in the art without description and variations which may be made in the structure without departing from the invention are also evident. 45

I claim:

In water heating apparatus, the combination of a lower heating coil composed of a tube of vertically elongated cross section, the convolutions of the tube being arranged approximately in conical form and just far enough apart to permit flame to pass between the two, and an approximately flat heating coil above the first, the coils being 50 55 connected in series.

NELSON G. GOREAU.
